UNITED STATES PATENT OFFICE.

HARRY WILLIS, OF DES MOINES, IOWA.

COLLAR-BUTTON AND NECKTIE-HOLDER.

SPECIFICATION forming part of Letters Patent No. 634,981, dated October 17, 1899.

Application filed November 4, 1898. Serial No. 695,519. (No model.)

To all whom it may concern:

Be it known that I, HARRY WILLIS, a citizen of the United States, residing at Des Moines, in the county of Polk and State of Iowa, have invented a new and useful Collar-Button and Necktie-Holder, of which the following is a specification.

My object is to provide improved means specially adapted to facilitate securing collars on shirts and maintaining neckties in proper position relative to a collar and collar-button and to prevent the annoyances incident to neckties becoming loose and slipping down and away from the collar-button at the front of the neck.

My invention consists in the separable collar-button and necktie-holder hereinafter set forth, pointed out in my claims, and illustrated in the accompanying drawings, in

Figure 1 is a sectional view, and Fig. 2 a top view, showing the peculiar form of the head of the button on the end of a tubular stem specially adapted for detachably connecting a necktie-holder therewith. Fig. 3 is a perspective view of the detachable necktie-holder, showing the main portion made of wire. Fig. 4 is a perspective view showing a necktie in position relative to a collar and a necktie-holder connected with the collar-button, as required, preparatory to tying bows with the necktie.

The letter *a* designates a button that may vary in size and form, as desired, and *b* is a tubular stem adapted to be passed through coinciding buttonholes in the front of the fixed collar of a shirt and the overlying ends of a shirt-collar. The face of the head on the end of the stem is convex and has a transverse depression or groove. An aperture *c* in the center of the top or head coinciding with the open top of the tubular stem that is adapted to admit a portion of the necktie-holder and, as required, to detachably fasten the two separable parts together for practical use and to prevent the necktie-holder from rotating relative to the head and stem of the button.

The necktie-holder is made of a single piece of wire, as shown in Fig. 3, by bending one end of the longest straight portion *d* into a hook *f*, and the other end portion into a hook *g* to jointly serve as a loop or clasp through

which a necktie can be extended, as shown in Fig. 4, before it is tied into a bow. A V-shaped spring *h* is fixed to the center of the loop and is adapted to be pressed through the aperture *c* in the head into the tubular stem *b*, so that the projection will press against the edges of the aperture in the head of the tubular stem with sufficient force to retain it in place when it is inserted in the button. The friction between the two parts prevents longitudinal movement of the part *h*, and the transverse depression across the convex face of the head through which the central part of the necktie-holder extends prevents rotary motion of the necktie-holder relative to the stem and head of the collar-button, and this is an essential feature in the satisfactory use of the invention. The free end of the spring *h* is elbow-shaped, and thereby adapted to be engaged by a person's fingers to facilitate contracting the spring and detaching the necktie-holder from the button.

In practical use when a necktie is in proper position relative to a collar and the ends doubled over each other one end portion of the tie is passed upward between and under the hooks *f* and *g* and the other end portion extended downward, as shown in Fig. 4, so the ends can be then readily tied into a bow or double bow in such a manner that the button and tie-holder will be entirely concealed and the necktie securely retained in proper position. To detach the necktie-holder from the button, the free end portion of the V-shaped extension is pressed inward and then withdrawn from the tubular stem of the button through the aperture in the head of the button.

By forming a depression in the top of the button, as shown in the drawings, the introduction of the V-shaped branch *h* of the tie-holder into the tubular stem of the button is greatly facilitated.

I claim as my invention—

1. A separable collar-button and necktie-holder comprising a collar-button having a tubular stem provided with a head having a convex face and a groove extending across said convex face and an aperture coinciding with the end of the tubular stem, and a necktie-holder consisting of an open loop having a V-shaped spring extending at right angles from the center of the loop and the free end of the

spring extended outward as shown and described, arranged and combined to operate in the manner set forth for the purposes stated.

2. A collar-button having a tubular stem *b*,
5 a head having a convex face, a transverse groove across said convex face and an aperture *c* coinciding with the tubular stem, a necktie-holder consisting of a straight part having ends *f* and *g* extending toward its center and a V-shaped spring *h* fixed to the cen-

ter of the straight part of the loop and having an elbow-shaped free-end portion extending at right angles from the spring arranged and combined as shown and described, for the purposes stated.

HARRY WILLIS.
